UNITED STATES PATENT OFFICE.

SAMUEL SEGAL, OF NEW YORK, N. Y., ASSIGNOR TO SEGAL METAL PRODUCTS COMPANY, INC., OF NEW YORK, N. Y., A CORPORATION OF DELAWARE.

ADJUSTABLE LOCK CASING.

Application filed April 7, 1921. Serial No. 459,258.

To all whom it may concern:

Be it known that I, SAMUEL SEGAL, a citizen of the United States, and a resident of New York, in the county of New York and 5 State of New York, have invented certain new and useful Improvements in Adjustable Lock Casings, of which the following is a specification.

My invention relates to locks for doors or 10 other closures in which the locking bolt of the lock shall be adapted to interlock with a suitable keeper fastened to the door frame or other support.

The object of the invention is the production of a lock, the casing of which shall 15 be adjustable in any direction without disturbing or changing the position of the spindle or other means adapted to actuate the lock mechanism and operated by a key 20 from without the door.

Other and further objects and advantages of the invention will appear from the accompanying description, the invention consisting in the novel parts and combinations 25 of the same hereinafter more particularly described and then specified in the claims.

In ordinary locks it frequently happens that the locking bolt is thrown out of alignment with the keeper and will not interlock 30 with the same due to the warping or sagging of the door or door frame or because of other reasons which prevents the lock from functioning until the lock or the keeper is entirely removed and its position readjusted. It is to obviate these objections and 35 disadvantages that I have devised my present invention.

Referring to the drawings illustrating a practical embodiment of the invention:

40 Fig. 1 is a front elevation of a lock casing applied to a door and embodying my invention.

Fig. 2 is a front elevation of a plate fastened to the door and to which the lock 45 casing is removably secured.

Fig. 3 is a rear elevation of the lock casing.

Fig. 4 is a view similar to Fig. 3 with the cover plate removed.

50 Fig. 5 is a front elevation of the cover plate of the lock casing.

Fig. 6 is a horizontal section on the line 6—6 of Fig. 1.

Fig. 7 is a vertical cross-section on the line 7—7 of Fig. 1. 55

Fig. 8 is a vertical cross-section on the line 8—8 of Fig. 1.

Fig. 9 is a vertical cross-section on the line 9—9 of Fig. 3.

Fig. 10 is a section on the line 10—10 60 of Fig. 3.

Referring in detail to the drawing:

The casing of a lock is indicated at 1 and is provided with horizontal slots 2 at

that end thereof which extends beyond the 65 edge of a door 3 when the lock is in mounted position on the door. 4 is a locking bolt

slidable vertically on tracks 5 within the 70 casing and provided with hooked ends or fingers 6 normally concealed by said cas-

ing and adapted to span or extend across 75 said slots 2 when in locked position and to interlock with the perforated ears of a suit-

able keeper (not shown) fastened to the 80 door frame. Said locking bolt is provided

with lugs 7 thereon with a space 8 inter- 85

mediate said lugs and with a pin 9 secured thereto. A tumbler pawl is indicated at 10

and is pivoted to said locking bolt 4 as at 90

11. Said tumbler pawl is provided with an arm 12 normally extending within the 95

space 8 intermediate the lugs 7 and with a shoulder 13 normally engaging a post 14

fastened to the outer wall of the casing. A 100

spring 15 is secured to the upper end of the tumbler pawl 10 and engages the pin 9. The action of said spring tends to swing 105

the tumbler pawl 10 on its pivot 11 in a clockwise direction whereby the arm 12 will

extend intermediate the lugs 7 and the 110

shoulder 13 will engage the post 14. The engagement of said shoulder and post holds the 115

locking bolt in raised and unlocked position

in an obvious manner.

120 16 indicates an operating knob mounted on the front wall of the casing and pro-

vided with a shank extending through said

wall to which is secured the operating fin-

gers 17 normally held in vertical alignment

and in inoperative position by a spring 18,

fastened to a wall of the casing. To throw

the operating bolt into locked position the

knob 16 is turned or rotated against the ac-

on its pivot 11 in a counter-clockwise direction against the action of spring 15 to release the shoulder 13 from engagement with post 14. Further movement of the finger 17 causes the same to engage and press downwardly against the lower lug 7 to cause the locking bolt 4 to slide downwardly on the tracks 5 whereby the hooks or fingers 6 are thrown into locked position across the slots 2. When the locking bolt reaches its lower or locked position a shoulder 19 thereon engages the under side of post 14 to hold the bolt in this position. To raise the bolt into unlocked position the reverse movements of those just described are effected by manipulation of the knob 16 which requires no detailed description as this type of bolt is old in the art and its operation is now well understood.

20 20 indicates a cylinder of an ordinary pin tumbler lock mounted in an annular opening 21 in the door 3, and carrying on the forward end thereof a conventional form of escutcheon plate 22 engaging the outer face of said door. Said cylinder is provided with the usual ears 23 preferably integral therewith and extending laterally therefrom. The door is provided with a shoulder 24 adjacent the end of the opening 21 on which is seated a plate 25 provided with an opening 26 therein. The cylinder is held in mounted position in said annular opening 21 by means of screws 27 which extend through said plate 25 and which are threaded through the ears 23. 28 indicates a spindle operatively connected with the key plug (not shown) of the cylinder and which is adapted to be rotated to actuate the lock mechanism when the proper key is inserted in said key plug from without the door and is rotated as is well understood in the art. Said spindle extends through the opening 26 in the plate 25 as clearly shown in Fig. 6.

45 A removable cover constituting the rear wall of the lock casing 1 is indicated at 29. Said cover is adapted to be fastened to said casing by a screw 30 extending therethrough and threading within the post 14. Said cover is provided with slots 31 and with an enlarged annular opening 32 within which is mounted a rotatable ring-shaped actuator 33 extending therethrough and provided with a flange 34 engaging the inner face of the cover, said flange being provided with an actuating finger 35 adapted to engage the lugs 7 and arm 12 to actuate the lock mechanism in the same manner as the fingers 17. The opposite side of said actuator is provided with a flange 36 engaging the outer face of the cover 29, said flanges 34 and 36 acting to retain the actuator 33 in mounted position in the opening 32 in said cover and prevent its withdrawal therefrom. 37 indicates a ring secured to the flange 36 by pins 38 whereby a space or slot 39 ob-

tains intermediate said flange and ring. A flat bar 40 provided with a slot 40' is slidably mounted in said space 39 and is capable of movement therein in all directions limited in some cases by the pins 38 which 70 act as stops.

41 indicates a plate which is securely fastened to the door by means of screws 42. Said plate is provided with ribs 43 on the inner face thereof contacting with or engaging the door to leave spaces between said plate and door. 44 indicates enlarged rectangular openings in said plate and 45 is a depression provided with an enlarged annular opening 46 therein.

80 The lock casing is secured to the plate 41 by means of screws 47 passing through the front wall of the casing, through the slots 31 in the cover thereof, through the rectangular openings 44 and threading through 85 bars 48 which are interposed between the plate 41 and the door intermediate the ribs 43 and which are of sufficient length to permit them to span the rectangular openings 44 and to prevent their withdrawal through said rectangular openings. The ends of the screws 47 do not enter the door but the lock casing is firmly held to the plate 41 by the binding action of the bars 48 against the inner surface of said plate, the ribs 43 acting as stops to prevent rotation of said bars when the screws 47 are tightened or loosened.

90 The operating spindle 28 not only extends through the opening 26 in the plate 25 but also through the enlarged opening 46 in the depression 45 of the plate 41, through the ring 37 and through the slot 40' of the bar 40. When said spindle is rotated by means of a key inserted in the key plug from without the door the bar 40 is also of necessity rotated and its ends or the parts thereof adjacent its ends thereupon engage and press against the pins 38 to effect a rotation of the actuator 33. The actuating finger 35 is thus 100 rotated to actuate the lock mechanism as previously described.

105 It will be obvious from the foregoing description that the position of the lock casing may be adjusted in any direction either vertical, horizontal or diagonal without it being necessary to remove the casing and without changing or tampering with the pin tumbler portion of the lock or the operating spindle 28 thereof or the lock mechanism 110 within the casing. To effect a change of position of the casing the screws 47 are merely loosened and the casing moved to the desired position, after which the screws are tightened to securely hold the casing in the 115 adjusted position in the manner previously described. The large rectangular openings 44 through which the screws 47 extend permit the casing to be moved in any direction 120 for a material distance. Also the movement 125 for a material distance. Also the movement 130

or adjustment of the casing in any direction for a material distance may be effected without interference with the operating spindle 28 due to the large size of the opening 46 5 and ring 37 through which the spindle extends. The spindle is always operatively connected to the actuator 33 even when the position of the casing is adjusted as the bar 40 is capable of movement in any direction 10 without becoming disengaged from said actuator as has been explained. As will be also noted the plate 41 is of a size permitting access to be had to the screws 42 by loosening the screws 47 and shifting the position of the 15 casing even though the casing is secured to said plate so as to permit said casing and plate to be removed as a unit when so desired. This is of advantage as it makes for convenience of installation.

20 What I claim as my invention is:—

1. In a lock, a casing mounted on a support, a locking bolt mounted in said casing, an actuator for actuating said locking bolt and means connected to said actuator and extending through a wall of said casing and adapted to cause said actuator to function, said actuator being adapted to permit of the adjustment of the relative positions of said casing and said connecting means while retaining the connection between said means and actuator.

2. In a lock, a casing mounted on a support, a locking bolt mounted in said casing, an actuator mounted on a wall of said casing 35 for actuating said locking bolt and means connected to said actuator and adapted to cause said actuator to function, said actuator being adapted to permit of the adjustment of the relative positions of said casing and said 40 connecting means while retaining the connection between said means and actuator.

3. In a lock, a casing mounted on a support, a locking bolt mounted in said casing, an actuator carried by said casing for actuating 45 said locking bolt, a spindle connected to said actuator and adapted to be operated by a key inserted in the lock, said actuator being adapted to permit of the adjustment of the relative positions of said casing and said 50 spindle while retaining the connection between said spindle and actuator.

4. In a lock, a casing mounted on a support, a locking bolt mounted in said casing, an actuator carried by said casing for actuating 55 said locking bolt, a spindle connected to said actuator and adapted to be operated by a key inserted in the lock to cause said actuator to function, said actuator being adapted to permit of the adjustment of the 60 relative positions of said casing and said spindle while retaining the connection between said spindle and actuator.

5. In a lock, a plate secured to a support, a lock casing mounted on said plate and containing the locking mechanism and means

associated with said plate for holding said casing to said plate and adapted to permit of the adjustment of the relative positions of said casing and plate while said casing is in mounted position.

6. In a lock, a plate secured to a support, a casing removably fastened to said plate, a locking bolt mounted in said casing, an actuator for said locking bolt and means extending through said plate and connected 70 to said actuator and adapted to be operated by a key inserted in the lock, said plate having means permitting the adjustment of the position of said casing in any direction while retaining said connecting means in operative 75 position.

7. In a lock, a plate secured to a support and provided with openings therein, bars spanning said openings, a lock casing containing the locking mechanism and means 80 engaging said casing and passing through said openings and engaging said bars to detachably fasten said casing to said plate.

8. In a lock, a plate secured to a support and provided with openings therein, bars 90 spanning said openings, a lock casing containing the locking mechanism, screws passing through said casing and said openings and engaging said bars to detachably fasten said casing to said plate and means for preventing rotation of said bars.

9. In a lock, a plate secured to a support and provided with openings therein, means on said plate engaging said support and forming spaces intermediate said plate and 100 said support, bars spanning said openings, a lock casing containing the locking mechanism and screws passing through said casing and said openings and engaging said bars to detachably fasten said casing to said plate, said means on said plate being 105 adapted to engage said bars to prevent rotation thereof.

10. In a lock, a plate secured to a support, a casing removably fastened to said plate, a locking bolt mounted in said casing, an actuator for said locking bolt, means extending through said plate and connected to said actuator and adapted to be operated by a key to cause said actuator to function 110 and means associated with said plate adapted to permit of the adjustment of the position of said casing in any direction, said actuator being adapted to permit such adjustment while said connecting means and actuator are in engagement.

11. In a lock, a plate secured to a support, a casing removably fastened to said plate, a locking bolt mounted in said casing, an actuator for said locking bolt carried by said casing, a spindle extending through said plate and connected to said actuator and adapted to be operated by a key inserted in the lock to cause said ac- 125

tuator to function and means associated with said plate adapted to permit of the adjustment of the position of said casing in any direction, said actuator being adapted to permit such adjustment while said spindle retains the same position and while said spindle and actuator are in engagement.

12. In a lock, a plate secured to a support, a casing removably fastened to said plate, a locking bolt mounted in said casing, an actuator associated with said casing for actuating said locking bolt and means extending through said plate and connected with said actuator and adapted 10 to be operated by a key inserted in the lock, said plate being adapted to be removed from said support while said casing is fastened to said plate.

13. In a lock, a casing removably fastened to a support, a locking bolt mounted in said casing, an actuator carried by said casing for actuating the locking bolt, a spindle adapted to be operated by a key and movable means operatively connecting 20 said spindle and actuator whereby movement of said casing may be effected while retaining said operative connection.

14. In a lock, a casing removably fastened to a support, a locking bolt mounted in said casing, a rotatable actuator mounted 30 on said casing for actuating said locking bolt, a spindle adapted to be operated by a key inserted in the lock and a movable bar carried by said actuator and operatively connecting said spindle and actuator whereby movement of said casing may be effected 35 while retaining said operative connection.

15. In a lock, a casing fastened to a support, a locking bolt mounted in said casing, an actuator mounted in a wall of said casing for actuating said locking bolt and provided with a slot and an opening therein, a movable bar within said slot and a spindle adapted to be operated by a key inserted in the lock and extending through 40 said bar and into said opening.

Signed at New York, in the county of New York and State of New York, this 6th day of April A. D. 1921.

SAMUEL SEGAL.
